Peter Crim of Maynardboro' Pennsylvania
Letters Patent

The schedule referred to in the Letters Patent and making part of the same containing a description, in the words of the said Peter Crim himself of his improvement in the Double Sspsontine Spring Saddle.

Do it known that of Peter Crim, of Maynardboro' in the County of Franklin and State of Pennsylvania, have made a new and useful improvement in saddles, and called "Crim's improved double Sspsontine Spring Saddle" which is described as follows, reference being had to the annexed drawing of the same making part of this Specification. The tree is constructed in the usual manner, to receive a piece of steel forming the spring bar C. The Sspsontine Spring D.D. The Web bar E, its ends being welded together or otherwise joined. It is a link which connects the two sides of the spring. this Spring is shaped to fit into its proper place under the tree.

A. A. H. represent the staples, bent around the spring, and secured to the tree at A. S. The spring is entirely covered with leather. The webbing K is to be attached to the web bar and carried back to the cantle where it is fastened at L. L.

What I claim as my invention in the above described saddle and not previously known is the peculiar formation of the double Sspsontine Spring and staples - these being so constructed as to connect, bond with the formation of the saddle, near the head, and being attached as before described, and particularly the application of the same to saddles either in Births or Earth seats.
